US00D624238S

(12) **United States Design Patent**
Turner

(10) **Patent No.:** **US D624,238 S**
(45) **Date of Patent:** **** Sep. 21, 2010**

(54) **DELIVERY DEVICE**

(76) Inventor: **Jeffrey D. Turner**, 21 Via Cristobal, San Clemente, CA (US) 92673

(**) Term: **14 Years**

(21) Appl. No.: **29/346,050**

(22) Filed: **Oct. 26, 2009**

(51) LOC (9) Cl. **27-01**

(52) U.S. Cl. **D27/101; D24/133**

(58) **Field of Classification Search** .... D24/133, D24/134, 135, 136, 137, 138, 139, 140, 141, D24/142, 143, 146, 150, 152, 144, 145, 147, D24/148, 149, 151, 153, 154, 127, 128, 129, D24/130, 107–108, 112, 111, 200; D27/100, D27/101, 170, 183; D23/233, 235; D8/40, D8/47, 57, 60, 67, 68, 69, 80, 82, 83, 84, D8/93, 94, 97, 107; 600/184, 220–223, 224, 600/225–227, 201–203, 210–218; 606/7, 606/86 A, 86 B, 119, 129, 186; 81/9.22; 604/48; 131/270–273, 360, 194

See application file for complete search history.

(57) **CLAIM**

The ornamental design for a delivery device, as shown and described.

DESCRIPTION

FIG. 1 is a top, rear, left side perspective view of the delivery device;

FIG. 2 is a rear view of the delivery device of FIG. 1;

FIG. 3 is a left side view of the delivery device of FIG. 1, the right side view is a mirror image thereof; and,

FIG. 4 is a top plan view of the delivery device of FIG. 1.

The broken lines are directed to environment and are for illustrative purposes only; the broken lines form no part of the claimed design.
